UNITED STATES PATENT OFFICE

CHARLES W. LESTER, OF SCHENECTADY, NEW YORK

LOCOMOTIVE STEAM DOME

Application filed September 29, 1932. Serial No. 635,353.

This invention relates to locomotive steam domes.

An object of the present invention is to provide an improved locomotive steam dome designed to receive steam from the locomotive boiler to which the dome is applied, and to separate any water mixed therewith from said steam, so that a substantially drier steam may be delivered to the dry pipe than has heretofore been possible.

Other objects and advantages achieved by the present invention will be apparent from the following description.

The invention is illustrated in the accompanying drawing, wherein: Figure 1 is a side view, diagrammatically shown, of a locomotive boiler with the steam dome of the present invention applied thereto; Fig. 2 is an enlarged longitudinal vertical section of the steam dome of the present invention connected with an end of a dry pipe, on the line II-II of Fig. 3; Fig. 3 is an enlarged fragmentary plan view of the steam dome, a part of the upper portion thereof being broken away; Fig. 4 is an enlarged front end view of the dome; Fig. 5 is a section on the line V-V of Fig. 2; Fig. 6 is a section of the auxiliary dry pipe of the steam dome on the line VI-VI of Fig. 2; and Fig. 7 is a section of the auxiliary dry pipe of the steam dome on the line VII-VII of Fig. 2.

Referring descriptively to the drawing, illustrating an approved embodiment of the present invention, the steam dome, indicated generally by the numeral 1, comprises a receptacle, constructed, in the embodiment illustrated, of cast steel. The dome 1 is provided with a lower portion 2, adapted to extend downwardly into a locomotive boiler, and an upper portion 3 adapted to extend upwardly above the upper surface of the boiler, as hereinafter described. The lower portion 2 comprises a bottom wall 4, side walls 5, and front and rear end walls 6 and 7 respectively. The lower portion 2 is of general box-shaped construction and is strengthened by an inner central, longitudinal, vertical wall 8 and spaced, transverse, vertical walls 9. The upper portion 3 is curved in cross-section, thereby providing

the required strength, no strengthening walls therefore being necessary. A lateral outwardly extending flange 10 surrounds the entire dome at the jointure of the lower and upper portions 2 and 3. The flange 10 is curved so as to conform with the upper surface of the locomotive boiler shell to which the dome is attached. At the sides and ends of the upper portion 3, the dome is connected with the flange 10 by strengthening webs 11.

Referring to Fig. 1, a locomotive boiler shell, indicated generally by the numeral 12, is provided with a suitable orifice in its upper portion for the reception of the steam dome 1. The dome 1 is applied to the shell 12, with its lower portion 2 extending into the boiler through said opening, its upper portion 3 extending above the boiler shell, and its flange 10 embracing the shell and secured thereto by rivets (not shown), suitable rivet holes 13 being provided in the flange 10 for this purpose.

At the forward end of the dome a dry pipe connection 14 is formed integrally with the walls of the dome. The connection 14 extends vertically from the bottom of the top of the dome, opening through the bottom wall of the dome. The lower portion 15 of the connection 14 is cylindrical, constituting a conduit, its axis being vertical, and the upper portion 16 is cylindrical about a horizontal axis. The upper portion is contracted and open at both its ends, for the reception of an auxiliary dry pipe 17. The forward side of the lower portion of the connection merges with and comprises a part of the wall 6, and the rearward side of the connection is joined to the front end of the longitudinal strengthening wall 8.

The auxiliary dry pipe 17 is longitudinally disposed in the upper portion 3 of the dome and extends substantially throughout the length thereof, its forward end passing through the open ends of the upper portion 16 of the connection 14 in sliding fit therewith. The forward portion of the auxiliary dry pipe 17 which is disposed within the connection 14, is provided with circumferentially spaced elongated openings 18, and small openings 19 are formed in the top

of the auxiliary pipe at the rear of the connection 14.

An opening 20 is provided in the forward end of the upper portion 3 of the dome, 5 through which opening the auxiliary dry pipe 19 is inserted into the dome, in assembling the apparatus. The opening 20 is closed by a cover 21, secured to the dome by studs 22, an annular ball seat 23 being 10 provided between the cover 21 and the adjacent wall of the dome, around the opening 20, to insure a steam-tight connection. The forward end of the auxiliary dry pipe 17 is seal-welded to the connection 14 as 15 indicated at 24. The auxiliary dry pipe is closed at its rear end by a head 25, suitably welded thereto, as indicated at 26. The auxiliary dry pipe is supported at its rear end by a bolt 27, which is screwed 20 through the rear end wall of the upper portion 3 of the dome and through the center of the head 25, the bolt 27 being riveted over at its outer end to provide a steam-tight fit.

25 Holes 28, for the admission of steam from the boiler, are provided in the sides 5 and ends 6 and 7 of the lower portion 2 of the dome, and holes 29, are provided in the bottom 4 of the lower portion of the dome for 30 the return to the boiler of water separated from the steam in the dome.

A main dry pipe 30, which is connected at its forward end in the usual manner (not shown) with the distribution valves of the 35 locomotive to which the dome is applied, is connected at its rear end by an elbow 31 with the lower end of the connection 14. A strap or other suitable means (not shown) is provided to support the elbow and dry pipe, 40 as in usual practice, and an annular ball seat, similar to the seat 23, is provided between the upper end of the elbow 31 and the connection 14, to provide a steam-tight fit.

In the operation of a locomotive embodying the aforescribed steam dome of the 45 present invention, steam is admitted into the dome through the openings 28 in the side and end walls of the lower portion 2. These openings being relatively small, any 50 water that is mixed with the steam tends to be separated from the steam during its passage through the openings. The steam within the dome then passes into the auxiliary dry pipe through the small openings 19 in 55 the top thereof and any remaining water which may have passed through the openings 28 is subjected to a second separating action by the openings 19 before the passage of the steam into the auxiliary dry pipe. The water separated from the steam 60 passes back, through the holes 29 in the bottom of the lower portion 2, to the boiler. The steam having entered the auxiliary dry pipe passes through the openings 18, then 65 into the connection 14, and thence into the

main dry pipe 30. It will be apparent that the improved steam dome provides a means for delivery of steam from the boiler to the dry pipe whereby substantially all water is separated therefrom, or in other words, 70 by means of the improved steam dome, relatively very dry steam is delivered to the dry pipe.

While there has been hereinbefore described an approved embodiment of the present invention, it will be understood that many and various changes and modifications in form, structure, and arrangement may be made without departing from the spirit 75 of the invention, and that all and any such changes and modifications as fall within the scope of the appended claim are contemplated as a part of the present invention.

The invention claimed as new and desired to be secured by Letters Patent is:

A locomotive steam dome comprising, as a unitary casting, a peripheral flange for attachment to the margin of an opening in the top of a boiler, a box-shaped portion below said flange adapted to extend within said boiler provided with small openings through its side walls for admission of steam from said boiler and openings in its bottom wall for egress of water from said dome to said boiler, longitudinal and transverse vertical walls reinforcing the box-shaped portion, a vertical passageway open at its bottom for connection with a dry pipe and having an upper opening in its side wall transverse of said dome, and a dome-shaped portion above said flange adapted to extend beyond said boiler, and having an opening at one end; a closure for said dome-shaped portion opening, said upper opening being disposed in said dome-shaped portion and in alignment with said dome-shaped portion opening; a removable drum disposed in said dome-shaped portion of a size in cross section to be admitted through said dome-shaped portion opening, 100 disposed within said dome-shaped portion longitudinally thereof, having an end portion disposed within said upper opening, engaging the wall thereof with a sliding fit and having its opposite end closed; and means for supporting said drum connected to said dome at said closed end of said drum, the opposite end portion of said drum being in communication with said vertical passageway, and said drum being provided with 105 orifices to admit steam to said drum from said dome.

CHARLES W. LESTER.
